RATCHET MECHANISM.

1,388,929.

Specification of Letters Patent. Patented Aug. 30, 1921.

Application filed October 5, 1920. Serial No. 414,899.

To all whom it may concern:

Be it known that I, EDWIN W. BULLARD, a citizen of the United States, residing at Whitneyville, in the county of New Haven 5 and State of Connecticut, have invented a new and useful Improvement in Ratchet Mechanisms; and I do hereby declare the following, when taken in connection with the accompanying drawings and the characters 10 of reference marked thereon, to be a full, clear, and exact description of the same, and which said drawings constitute part of this application, and represent, in—

Figure 1, a view in side elevation of a bit-brace embodying my improved ratchet mechanism, the crank-lever of the brace being broken away.

Fig. 2, a plan view thereof.

Fig. 3, an enlarged view thereof in vertical central longitudinal section.

Fig. 4, an enlarged view in vertical transverse section on the line 4—4 of Fig. 3.

Fig. 5, a view in central horizontal section on the line 5—5 of Fig. 3, the pawl-operating ring being positioned to permit both pawls to be engaged with the ratchet.

Fig. 6, a corresponding view with the pawl-operating ring turned to disengage one of the pawls from the ratchet.

Fig. 7, a detached perspective view of the pawl-operating ring.

Fig. 8, a detached view, partly in plan and partly in horizontal section of one of the pawls.

Fig. 9, a view thereof in side elevation.

Fig. 10, a view thereof in front elevation.

My invention relates to an improved ratchet mechanism of the type in which a pair of complementary, longitudinally-slidable contacting pawls are employed to coact with a ratchet, the object of the invention being to produce a simple, convenient and reliable mechanism of the character described.

With these ends in view, my invention consists in a ratchet mechanism characterized by an oscillatory pawl-operating ring mounted in a slot in the ratchet-sleeve of the housing and adapted to coact with the adjacent ends of the respective pawls to permit their simultaneous or alternate engagement with the ratchet.

My invention further consists in certain details of construction and combination of

parts as will be hereinafter described and 55 pointed out in the claims.

In carrying out my invention as herein shown, I employ a pawl-operating ring 11 located for oscillatory movement in a transverse slot 12 formed in the ratchet-sleeve 13 60 of the housing 14, into which the slot also extends for a short distance, as clearly shown in Figs. 5 and 6. The said ring 11 is positioned by and turns upon a ratchet 15 located within the sleeve 13 which is integral with the housing 14 and stands at a right angle to the longitudinal axis thereof. The outer edge of the ring is knurled and projects just enough beyond the surface of the sleeve for being gripped by the user of the 70 tool. That portion of the ring lying within the inner end of the slot 12, is formed with a segmental notch 16 adapted in length to permit the noses of a pair of complementary, longitudinally-slidable, contacting, 75 semicircular pawls 17 and 18 to be simultaneously engaged with the teeth of the ratchet, as shown in Fig. 5, these pawls being located in a circular bore 19 formed in and concentric with the housing. The outer 80 end of the bore 19 receives one end of a bit-brace crank-lever 20 fastened by a transverse pin 21. Helical springs 22 interposed between the inner end of the crank-lever and the inner ends of the respective pawls 85 provide for constantly urging them into contact with the teeth of the ratchet, the said springs entering holes 23 formed in the inner ends of the pawls.

For coaction with the ring 11, the nose 90 ends of the pawls are formed with transverse slots 24, adapting the nose ends of the pawls to straddle, as it were, the ring. The bottom wall 25 of each slot 24 has its outer end inclined as at 26 and its inner end beveled as at 27. The nose end of each pawl is also beveled to form a ratcheting face 28 for coaction with the teeth of the ratchet. The end walls 29 of the notch 16 in the ring 11 coact at their extreme outer ends with the 100 inclined faces 26 of the pawls to retire them against the tension of the helical pawl springs 22, and thus disengage the noses of the pawls from the teeth of the ratchet. The said walls 29 also act as stops, as shown in 105 Fig. 6, to limit the oscillatory movement of the ring 11 in either direction. For the purpose of locking the ring in either of its op-

erative positions, its edge is cut away adjacent to the outer ends of the walls 29, to form detent teeth 30 which coact with the bevels 27 of the pawls, as shown in Fig. 6, to yieldingly lock the ring, which, when so locked, can only be rotated by applying sufficient force to it to slightly compress the springs 22 and so permit the teeth 30 to ride out of engagement with the bevels 27. The 10 inner faces of the nose ends of the pawls are formed with driving notches 31 coacting positively with the ratchet teeth for turning the ratchet and driving the chuck 32, carried by the chuck head 33 of the ratchet 15, which is secured in place by a screw 34, and a washer 35, which latter fits into a recess 36 in the upper end of the sleeve 13.

When the ring 11 is turned into its intermediate position, as shown in Fig. 5, both 20 pawls are permitted to ride over it, as it were, into engagement with the teeth of the ratchet, now locked positively to the crank-lever 20. When, however, the ring is turned in one direction or the other, one of the 25 pawls is retired out of engagement with the ratchet teeth, as shown in Fig. 6, in which adjustment the ratchet will be driven when the crank-lever is swung in the direction of the arrow *a*, and idly ratchet back when the 30 crank-lever is swung in the direction of the arrow *b*.

I claim:

1. A ratchet mechanism having a housing provided with a ratchet-sleeve having a 35 transverse slot, a ratchet located in the said sleeve, two longitudinally-slidable contacting pawls located in the said housing and coacting with the said ratchet, and a pawl-operating ring located in the slot in the ratchet-sleeve and coacting with the nose ends of the pawls for disengaging one or the other of the same from the ratchet.

2. A ratchet mechanism having a housing provided with a ratchet-sleeve having a 45 transverse slot, a ratchet located in the said sleeve, two longitudinally-slidable contacting pawls located in the said housing and coacting with the ratchet, and an oscillatory pawl-operating ring located in the said slot, positioned by and turning upon the said ratchet and coacting with the nose ends of the pawls for operating the same.

3. A ratchet mechanism having a housing provided with a ratchet-sleeve having a transverse slot, a ratchet located in the said sleeve, two longitudinally-slidable contacting pawls located in the said housing and coacting with the ratchet, and an oscillatory pawl-operating ring located in the said slot, encircling the said ratchet and formed with 55 a notch adapted at its ends to coact with the pawls, when the ring is turned, to disengage the pawls from the ratchet and yieldingly lock them in such disengaged positions.

4. A ratchet mechanism having a housing provided with a ratchet sleeve having a transverse slot, a ratchet located in the said sleeve, two longitudinally-slidable contacting pawls located in the said housing and having their nose ends transversely slotted and formed with operating and locking surfaces, and a pawl-operating ring installed in the slot in the ratchet-sleeve and formed with a notch and adapted at the ends of the 60 said notch to coact with the bottom walls of the slots in the nose ends of the pawls to disengage the pawls from the ratchet and yieldingly lock them in such disengaged positions.

5. A ratchet mechanism having a housing provided with a ratchet sleeve having a transverse slot, a ratchet located in the said sleeve, two longitudinally-slidable contacting pawls located in the said housing and having their nose ends transversely slotted, and an oscillatory pawl-operating ring installed in the said slot of the ratchet-sleeve and formed with a segmental notch the end walls 70 of which act as stops for limiting the oscillatory movement of the ring and the outer ends of the said walls coacting with the slots in the nose ends of the pawls for disengaging the same from the ratchet and the ring being adapted at either end of the said notch 75 for coacting with the pawls for yieldingly locking them in their disengaged positions.

In testimony whereof, I have signed this specification in the presence of two subscribing witnesses.

EDWIN W. BULLARD.
